CARPET.

No. 15,869.

Patented Feb. 24, 1885.

UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 15,869, dated February 24, 1885.

Application filed January 14, 1885. Term of patent 3½ years.

To all whom it may concern:

Be it known that I, W. L. JACOBS, of East Orange, New Jersey, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

The face of the design is loosely overlaid with various large conventionalized flower and leaf figures having angular outlines and carried on right-lined connecting-stems. The

ground between these figures is irregularly filled in with blocks of checker-work, square 20 and diagonally arranged, all as clearly shown in the photograph. The flower and leaf system does not interblend with but simply over-lies the checkered ground.

I claim—

1. The design for a carpet, consisting of the system of connected flower and leaf figures, substantially as shown and described.
2. The design for a carpet, consisting of the system of connected flower and leaf figures 30 and the underlying checkered ground, substantially as shown and described.

W. L. JACOBS.
